UNITED STATES PATENT OFFICE.

JAMES A. GREENLEE, OF CHICAGO, ILLINOIS, AND HERMAN WEGWART, OF BURLINGTON, WISCONSIN.

BASKET OR RECEPTACLE.

1,153,906.

Specification of Letters Patent. Patented Sept. 21, 1915.

Application filed May 23, 1914. Serial No. 840,467.

To all whom it may concern:

Be it known that we, JAMES A. GREENLEE, and HERMAN WEGWART, citizens of the United States, and residing, respectively, at 5 Chicago, Cook county, Illinois, and Burlington, Racine county, Wisconsin, have invented certain new and useful Improvements in Baskets or Receptacles, of which the following is a specification.

10 Our invention relates to baskets and similar receptacles and more particularly to the construction of baskets of the diamond braided splint type and to the means for locking the cover thereon.

15 One of the objects of our invention is to construct a basket or receptacle of this type in a manner so that the walls thereof are strong and durable and capable of withstanding considerable lateral strain in both 20 a loaded and unloaded condition.

Another object is to provide the basket or receptacle with a suitable cover that can be securely locked in place in a novel manner and by novel means which assist in adding 25 to the strength of the basket.

These objects and others which will be obvious to those skilled in the art we accomplish by the means and in the manner hereinafter fully described and as more particularly pointed out in the claims, reference 30 being had to the accompanying drawings forming a part of this specification, in which:

Figure 1 is a vertical longitudinal side 35 elevation of a basket or similar receptacle made in accordance with our invention; Fig. 2 is a vertical end elevation thereof having the cover removed; Fig. 3 is a top plan view thereof having a portion of the top or cover 40 broken away to disclose the construction thereof and the manner of braiding the splints of the basket or receptacle body; Fig. 4 is an enlarged fragmentary section taken on line 4—4, Fig. 1.

45 Heretofore in the manufacture of diamond-braided splint baskets and other receptacles for the packaging and shipping of various commodities, it has been customary to form the braids of single veneer splints, 50 and these splints were arranged so that those extending in one direction alternately lap over and under the group of splints disposed at an angle thereto. This construction has been found extremely undesirable for the 55 reason that the walls and bottoms of these

baskets were very fragile and could not be subjected to any great load or lateral pressure. In carrying out our improvements we arrange the diamond braiding so that the basket is formed with a double body and a 60 portion of the splints of one body are interlaced with splints of the other body.

Referring to Figs. 1, 2 and 3 of the drawings, it will be observed that our basket or receptacle comprises an outer body formed 65 by braiding suitable veneer splints A and B in the form known as the "diamond braids" or "basket weave" and internested therein is a separate inner body formed by similarly braiding veneer strips A' and B' 70 In order to form these bodies into an integral receptacle and interlock the same together, we prefer to interbraid or weave splints A and A' with the opposite splints B and B'. This interweaving or interbroiding of the splints of the two bodies we prefer to confine to the corner portions of the receptacle as shown although it is possible to interbraid them at any desired place.

75 Suitable straps or runners C are secured 80 preferably to the exterior of the basket or receptacle by tacking or otherwise fastening the same parallel to each other longitudinally upon the bottom and vertically upon the ends of the body. The upper edge of the 85 basket or receptacle is preferably finished off by securing the usual hoops or rims D, D', upon the exterior and interior thereof. The basket or receptacle is provided with a lid or cover that preferably comprises a strip 90 of veneer E somewhat thicker than the splints A, &c., and which is shaped to conform to the contour of the finished upper edge or rim. Strengthening or reinforcing cleats e, e', are secured respectively to the 95 upper and lower surfaces of this cover as shown, the cleat e' being slightly shorter than the width of the cover in order to accommodate the same to the inside of the basket or receptacle as shown.

100 The means for securing the cover in place comprises a fastening strip F of relatively narrow thin flexible metal one end of which is preferably inserted up between the hoop D and the adjacent splint A where it is 105 turned downwardly against the outer face of said hoop. The lower or longer portion of the metal fastening strip is then bent upwardly flat against the outer face of the hoop and then downwardly and inwardly 110

until it is flat upon the upper cleat *e* of the cover to which it is secured by tacks *f* that are driven therethrough into the cleat and cover plate.

5 Should it be desired to use the basket or receptacle several times only the fastening strips *F* on one side thereof should be loosened and it will be found that those on the opposite side will act as hinges that permit the cover to be raised but not removed from the top of the basket or receptacle.

10 From the above description it will also be seen that the cleats *e* will act as a cross-brace to the rim of the basket or receptacle and will materially assist the same against lateral strains.

15 Having thus described our invention what we claim as new and desire to secure by Letters Patent, is:—

20 1. A receptacle comprising a plurality of inner and outer braided bodies and having areas wherein the inner and outer bodies are braided with each other.

2. A receptacle comprising a plurality of

inner and outer braided bodies and having 25 areas wherein the inner and outer bodies are braided with each other, and hoops secured to the upper edges of said bodies.

3. A receptacle comprising a substantially rectangular shaped outer body and a correspondingly shaped inner body disposed therein, said inner and outer bodies comprising separate braided splints that interlock with each other at the corners of said receptacle, and hoops secured to the upper 30 35 edges of said bodies.

In testimony whereof we each affix our signatures in the presence of two witnesses.

JAMES A. GREENLEE.
HERMAN WEGWART.

Witnesses to signature of James A. Greenlee:

E. K. LUNDY, Jr.,
BENJ. T. ROODHOUSE.

Witnesses to signature of Herman Wegwart:
